VENDING MACHINE CABINET FRONT

Charles P. Peterson and Jerome M. Pappas, Jr.,
Greensboro, N. C.

Application May 25, 1955, Serial No. 36,208

Term of patent 14 years

(Cl. D52—3)

FIG. 1

FIG. 2

FIG. 3

Figure 1 is a perspective view of a vending machine cabinet front, showing our new design;

Fig. 2 is an enlarged sectional view taken substantially along the plane of line 2—2 of Fig. 1;

Fig. 3 is a reduced plan view of the cabinet front.

The characteristic features of the design reside in the solid line portions.

What is claimed is:

The ornamental design for a vending machine cabinet front, substantially as shown and described.
